(57) **CLAIM**

The ornamental design for a container and cap, as shown and described.

DESCRIPTION

FIG. 1 is a perspective view of the container and cap of our design.

FIG. 2 is a front elevation view thereof.

FIG. 3 is a rear elevation view thereof.

FIG. 4 is a right side elevation view, the left side elevation view being a mirror image thereof.

FIG. 5 is a top plan view thereof.

FIG. 6 is a bottom plan view thereof.

FIG. 7 is a perspective view of a second embodiment thereof, the only difference being that the container body is transparent.

FIG. 8 is a front elevation view thereof.

FIG. 9 is a rear elevation view thereof.

FIG. 10 is a right side elevation view, the left side being a mirror image thereof.

FIG. 11 is a top plan view thereof; and,

FIG. 12 is a bottom plan view thereof.

1 Claim, 10 Drawing Sheets
